UNITED STATES PATENT OFFICE.

HEMAN H. GRANGER, OF DAVENPORT, WASHINGTON, ASSIGNOR OF ONE-HALF TO
H. D. TRUNKY, TRUSTEE, OF SPOKANE, WASHINGTON.

HYGIENE HEATING AND COOLING SYSTEM.

Application filed January 30, 1928. Serial No. 250,372.

My present invention relates to improvements in hygiene heating and cooling systems adapted for use in private and public buildings, by means of which fresh air may be supplied at all times to the interior of the building and the air may be warmed in cold weather or the temperature of the atmosphere in the house may be reduced in summer, by the circulation of air currents to eject warm air or to introduce cooler air currents to the building.

The invention consists in certain novel combinations and arrangements of parts whereby air under forced draft may be supplied to the interior of the building, or the air currents passing to the building may be created under natural draft and in combination with the means for causing the drafts, a heating furnace is utilized for the purpose of heating the air. Means are provided in the ventilating system for washing or purifying the air before it is heated, and means are utilized for removing excess moisture from the air before it passes to the heating furnace.

In the accompanying drawings, I have illustrated one complete example of the physical embodiment of my invention in which alternate structures are employed in the ventilating system and in which the parts are combined and arranged according to the best mode I have so far devised for the practical application of the principles of my invention.

Figure 1 is a perspective view showing the ventilating system and disclosing two floors of a house that is equipped with the heating system;

Fig. 2 is a detail longitudinal, vertical, sectional view of the heating furnace and adjacent parts of the heating system as at line 2—2 of Fig. 3;

Fig. 3 is a transverse vertical section at line 3—3 of Fig. 2;

Fig. 4 is a perspective view showing the cold air flue partly broken away to disclose the air washing and air drying screens within the flue;

Fig. 5 is a transverse or horizontal sectional view of the hot air flue at line 5—5 of Fig. 1;

Fig. 6 is a perspective view showing one of the distributing heads connected with the branch hot air flues; and

Fig. 7 is a detail view showing the man-

ner of venting the smoke stack of the furnace or other flues built to carry off the cold air from the room being heated.

In the drawings in which the preferred embodiment of my invention is illustrated, I utilize a well known type of steam boiler 1 having the usual grate 2 and the combustion chamber 3 and above the combustion chamber are arranged the fire tubes 4 through which the smoke or gases of combustion pass from the rear of the furnace to the smoke chamber 5 in the front of the furnace. The smoke as usual passes from the smoke chamber up through the smoke pipe 6. The fire tubes are enclosed within a horizontally disposed cylindrical drum 7 and in the upper portion of this drum 7 are arranged horizontal air tubes or flues 8 which are air heating tubes and through which the air to be heated passes from the open rear end of the drum to the front of the drum and thence these heated air currents pass upwardly through the hot air tube 9 in the top of the drum and thence to the main hot air flue 10 which rises vertically from the drum and extends to the top-most floor of the building to be heated. On each of the floors, the main hot air flue is provided with laterals 11 which may be located at the ceiling or along the floor of the rooms and these laterals are fashioned with discharge heads or distributing heads which comprise a plurality of nozzles 12 through which the hot air is distributed to the room. A damper 13 is provided in each lateral 11 so that the passage of hot air currents through the distributing heads may be manually controlled in usual manner.

In order to prevent loss of heat by radiation from the main hot air flue 10, I provide a jacket 14 which forms a vacuum space 15 about the exterior of the main hot air flue, and a suction pipe 16 from this vacuum space extends to a vacuum pump 17 which is located in the basement or cellar of the building to be heated adjacent to the furnace. When the vacuum is in operation, air is drawn from the vacuum space 15 and therefore loss of heat by radiation from the main hot air flue 10 is prevented.

At the rear of the furnace, an air inlet chamber 18 is provided within the furnace walls and a partition 19 is extended from the rear wall of the furnace to the drum to complete this enclosure. A cold air port 20

is provided in the rear wall of the furnace and communicates with the air chamber 18 and a cold air gate 21 is hinged at 22 and provided with a crank handle 23. The 5 crank handle is accessible from the exterior of the furnace and this gate 21 may be turned upwardly to horizontal position as in Figs. 2 and 4 to permit passage of air currents through the port 20 to the chamber 10 18 and thence to the heating pipes or tubes 8. The cold fresh air is supplied to the furnace at the cold air port 20 from the cold air flue 24, and a fan blower 25 is used to create a forced draft of air through the 15 cold air flue. The fan blower has an intake pipe 26 and a hinged door 27 to regulate the quantity of air supplied to the pipe, and the discharge pipe 28 of the fan blower is connected with the cold air flue 24.

20 Within the cold air flue, I provide a reticulated screen or washer 29 over which water is designed to flow from the water pipe 30 and it will be apparent as the water slowly trickles or flows over this reticulated 25 washer, the moisture and screen will wash the air currents passing therethrough, and the excess water passes off through the drain pipe 31 below the cold air flue. In order to remove the excess moisture from the washed 30 or purified air, a second reticulated screen 32 is transversely disposed in the cold air flue and the presence of this screen or drier causes the removal of excess moisture from the air currents passing through the reticulated 35 screen. It will be understood that the cold air is drawn into the ventilating system by means of the fan blower and the air currents are forced through the heating tubes 8 and then the hot air currents pass 40 upwardly through the main hot air flue and are distributed by means of the nozzles in the heads of the laterals.

In some instances, it is desirable to use 45 natural draft instead of forced draft for supplying the air to the furnace and for this purpose, as shown in Fig. 3, I utilize side plates 33 within the furnace walls and connected with the exterior of the drum 7. These side plates form side flues 34 which 50 communicate with ports 35 in the side walls of the furnace and doors or gates 36 regulate and control the passage of cold air through these ports to the side flues 34. As the natural air currents moving upwardly pass over 55 the top of the drum to the main hot air flue 10 the air currents are heated and are then distributed as usual.

When it is desired to introduce fresh air 60 through the ventilating system without heating the air, as in summer time, the gate 21 is turned to vertical position to close the

port 20 from the air chamber 18 and this port then communicates with a cold air pipe 37 that extends from the port 20 up through the furnace and thence forward over the 65 top of the furnace to the main hot air flue 10. As thus arranged, the fan blower may be utilized to supply washed, moistened, and purified cool air currents to the interior of the house.

In Figs. 1 and 7, I illustrate a cold air port 38 in the smoke pipe by means of which cold air currents may be transferred from the floor portion of the room to the interior of the smoke pipe or air flues built for that purpose, and within the smoke pipe a deflector plate 39 is provided to guide the cold air currents and to prevent egress of smoke from the smoke stack. In this manner, as the 70 warm air currents are supplied to the upper portion of the room, the cold air currents are allowed to pass through the port 38 thus insuring a complete circulation of air in the dwelling with a continuous ventilation to insure fresh air at all times.

Having thus fully described my invention, what I claim as new and desire to secure by Letters Patent is—

1. The combination with a hot air heating furnace having a main hot air flue, and a cold air flue with an inlet port to the furnace, and a fan blower connected with said cold air flue, of means in the flue for wet-washing the air currents and means for subsequently extracting moisture from the washed air currents, laterals connected to the main hot air flue, and discharge heads connected to said laterals.

2. The combination with a hot air heating furnace having a hot air flue and means for distributing hot air currents, of a jacket around the hot air flue and means for causing a vacuum in the jacket, a cold air flue connected with the furnace and means for passing air currents through said cold air flue, wet-washing means within the cold air flue, and means within the cold air flue for subsequently eliminating excess moisture from the washed air currents.

3. The combination with a hot air heating furnace having a cold air flue with its port in the rear wall of the furnace and a cold air chamber between the furnace and said port, of a main hot air flue from the front of the furnace, means for supplying air under pressure through the cold air flue, an exterior cold air pipe from the port to the main hot air flue above the furnace, and a hinged gate for alternating flow of air from the port to the furnace or to said cold air pipe.

In testimony whereof I affix my signature.

HEMAN H. GRANGER.
